REEL

Garvie Lee Tolliver, Wyco, W. Va.

Application October 7, 1938, Serial No. 233,851

2 Claims. (Cl. 200—153)

This invention appertains to new and useful improvements in conductor reels such as are employed by miners in reeling or unreeling the usual shot lines.

5 The principal object of the present invention is to provide a reel with which is associated a switch for normally maintaining the shot line in a closed circuit so that wet rails and other damp structures cannot result in the shorting of the line 10 with the result that the shot is fired prematurely, frequently with mishaps.

An important object of the invention is to provide a reel which is of simple construction, and one which is easy to manipulate and convenient 15 to use in regard to the switch employed.

Other important objects and advantages of the invention will become apparent to the reader of the following specification.

In the drawing:

20 Figure 1 is a side elevational view of the switch structure.

Figure 2 is a top plan view of the reel with a portion adjacent the switch broken away.

Figure 3 is a side elevational view of the reel 25 showing the switch.

Referring to the drawing wherein like numerals designate like parts, it can be seen that numeral 5 represents a base plate of insulation along the front and rear edges of which are disposed the plates 6—6 from which rise the tubular metal posts 7—7 which are disposed to form the side rails 8. A brace member 9 is provided for the front and rear of the frame work, each of these braces extending upwardly from the base of the corresponding post 7 inclinedly, touching the horizontal front and rear bar 10 as at 11, and preferably welded thereto and extending downwardly to merge with the base portion of the corresponding front or rear post 7.

40 A pair of semi-circular shaped super-frame members 12—12 have their lower end portions secured to the horizontal front and rear bars 10, the upper portions of these frame members 12—12 being connected by the bridge member 13. A

45 handle 14 extends upwardly over the bar 13 from the frame members 12—12 and is preferably rubber covered to form an insulated handle.

Uprights 15 at each end of the frame serve to support the bearings 16 through which the shaft 50 17 is journaled. This shaft may be made up of telescopic sections and at one end is the hand crank 18 whereby the shaft and reel can be rotated.

The reel includes the side boards 19 preferably 55 of wood or some other suitable insulation be-

tween which extend the slats 20. Flanges 21 are provided on the axle shaft 17 and these are bolted or otherwise secured to the side boards 19 and 20 as at 22.

On one of the side boards 19 is the switch assembly generally referred to by numeral 23 and this consists of the plate 24 of insulation suitably secured in a pocket 25 in the outside of the board 19.

5 Adjacent the pocket 25 are the openings 26 through which the conductor wire of the shot line is disposed to connect to the point shank 28 on which is the binding post 30. The shank 27 has the binding post 29 to which a ground wire 29a is attached.

10 Clamp members 31—32 are employed on the plate 24 for clamping the shank 27 to the plate while the shank 29 is secured in place against a plate of insulation 33. The remaining end of the shank 28 is provided with the inturned foot 34 15 to which is clamped as at 35, the point 36. The remaining end of the shank 27 is provided with the offset 37 on which is the point 38 which is substantially longer than the point 36. A finger 39 is slidably disposed on the shank 27 between 20 the clamps 31—32 and against the action of the spring 40.

25 It can now be seen that with the shot line unreeled from the reel to a point where firing is safe, the operator can remove the finger 39 from 30 engagement with the foot 34 (see Figure 2) which will open the circuit of the shot line and the operator may now place his battery over the points 36 and 38 for charging the shot line with electricity for firing the shot.

35 Thus it can be seen that with the shot line forming a closed circuit by having the finger 39 engaging the foot 34, there is no likelihood of the shot being fired prematurely and this condition of the shot line will remain until the operator opens 40 this circuit by removing the finger 39, which of course will take place just momentarily before the battery is applied to the points 36 and 38.

45 While the foregoing specification sets forth the invention in specific terms, it is to be understood that numerous changes in the shape, size and materials may be resorted to without departing from the spirit and scope of the invention as claimed hereinafter.

Having described the invention what is claimed 50 as new is:

55 1. A shot line reel comprising a rotary reel spool, and a circuit-closing switch on the spool to which the line is connected, said switch having a battery-engaging point at each side thereof,

said switch means including a shank for each of the points and one of the shanks being grounded, a slideable finger on the grounded shank engageable with the foot of the other shank for maintaining a closed circuit with the shot line.

5 2. A shot line reel comprising a rotary reel spool, and a circuit-closing switch on the spool to which the line is connected, said switch hav-

ing a battery-engaging point at each side thereof, said points each including a shank, one of said shanks being grounded, the other shank being provided with a foot, said grounded shank having a movable finger thereon removably engageable with the said foot, and means on one shank whereby a shot line can be connected thereto.
